UNITED STATES PATENT OFFICE.

ALTON H. MOOERS, OF ELYRIA, OHIO.

SOFA-BED.

SPECIFICATION forming part of Letters Patent No. 715,114, dated December 2, 1902.

Application filed November 2, 1901. Serial No. 80,846. (No model.)

To all whom it may concern:

Be it known that I, ALTON H. MOOERS, a citizen of the United States, residing at Elyria, in the county of Lorain and State of Ohio, have invented new and useful Improvements in Sofa-Bedsteads, of which the following is a specification.

My invention relates to improvements in sofa-bedsteads in which the back of a sofa is let down into a horizontal position and in combination with the seat forming the foundation for a bed; and the object of my invention is to provide such a bed as will be simple and cheap in construction, easily operated, unlikely to get out of repairs, and can be used as a sofa when not used as a bed, easily convertible when desired, and sightly in appearance. I attain these objects by means of the mechanism illustrated in the accompanying drawings, in which—

Figure 1 is a perspective view of my invention when converted into the form of a sofa. Fig. 2 is a cross end section showing the position and relation of the parts when converted into a bed. Fig. 3 is a cross end section showing the position and relation of the parts when used as a sofa. Fig. 4 is a plan view of the framework of the bed, and Fig. 5 is a detailed view of locking device.

Similar letters refer to similar parts throughout the several views.

A and A' represent the parts forming the seat and back, respectively, of a sofa when so used, as shown in Fig. 1, and which form the mattress or foundation for a bed when placed in position. (Shown in Fig. 2.) These parts are suitably hinged and connected together at their inner edges. They are together of suitable width to form a bed when lying flat or horizontally and of any desired length to freely slide between the ends B B. The ends B B are of any suitable design, height, and width and rigidly connected together by means of the rails b b, which rails are also connected together by means of the cross-bars C C, all forming the frame of the bed. To each of the ends B B are pivoted connecting-bars a a, pivoted at a suitable point on the back A'. These bars a a should be connected at such a point on the ends of the bedstead and to the back A' and of such a length that when the front half A is pushed

back on the frame the rear part A' will be held up at a suitable height to form the back of a sofa and when dropped down will hold the inner edges of the parts A and A' in the longitudinal center of the bed-frame. To the under front edge and near the ends of the part A ratchet-teeth are secured. These teeth act against the front longitudinal rail b. The latter will serve as a stop-pawl when the seat is pushed back and hold the seat A from sliding forward on the frame of the bedstead. When engaged, they can be easily disengaged by lifting up on the part A, and thereby raise or lower the back part A', as desired, by either pushing back or pulling forward on the seat A.

To the lower sides and front edge near the ends of the back A' are attached hooks c c with an opening in the forward end and which hook under the ears c' c', rigidly secured to the cross-bars C C when the bed parts A and A' are in a horizontal position, thereby locking the center of the bed to the cross-bars C C and holding same from being raised by weight being applied to the outside edges of the bed parts A to A'.

The parts A and A' are carried or slide across the frame of the bed on the cross-bars C C. The side and cross bars may be made as wide as desired and the under part of the same may be covered with thin boards H or otherwise, and thereby form a suitable receptacle for bedding or other articles, which can be easily placed therein by raising the part A, as is obvious by inspection of the drawings. The seat k on bar C may serve as a stop or pawl, with which rack a engages.

The operations of my invention are simple and easy, as is obvious from the foregoing explanation and on examination of the drawings; that the parts A and A' can be made and upholstered in any style to suit the user, and that by simply drawing forward or pushing backward the part A the change is made from a sofa to a bed or from a bed to a sofa. That different angles can be given as desired to the back A' by the different engagements with the ratchet-teeth a'.

Having fully described my invention and its operations, what I claim as new, and desire to secure by Letters Patent of the United States, is—

In a sofa-bedstead, the combination of the frame having end pieces and longitudinal bars and cross-bars connected thereto, a seat and a back hinged together, connecting bars or links pivoted to the back and to the ends 5 of the frame, a rack near the front of the seat and a pawl on the frame with which said rack engages to hold the seat retracted and back raised, and a hook about central of one of the 10 cross-bars engaging a hook on the back when

the back is in horizontal position, all combined.

In testimony whereof I have signed my name to this specification in the presence of two subscribing witnesses.

ALTON H. MOOERS.
